VIDEO TAPE RECORDER

Ken Kira and Yoshimasa Fujimoto, both of Yokohama
Japan, assignors to Victor Company of Japan, Limited,
Yokohama, Japan

Filed Mar. 3, 1964, Ser. No. 78,854

Term of patent 14 years

Claims priority, application Japan Nov. 29, 1963

(Cl. D26—14)

Fig. 1.

Fig. 4.

Fig. 2.

Fig. 5.

Fig. 3.

Fig. 6.

Fig. 7.

*Fig. 8.**Fig. 9.*FIG. 1 is a front elevational view of a video tape recorder showing our new design;

FIG. 2 is a top plan view;

FIG. 3 is a bottom plan view;

FIG. 4 is a side elevational view as seen from the left side of FIG. 1;

FIG. 5 is a side elevational view as seen from the right side of FIG. 1;

FIG. 6 is a rear view;

FIG. 7 is a perspective view showing the recorder top and video screen unit;

FIG. 8 is a perspective view, similar to FIG. 7, but with the recorder top cover lowered; and

FIG. 9 is a perspective view, similar to FIGS. 7 and 8, but with both the tape recorder top cover and the video screen unit lowered.

We claim:

The ornamental design for a video tape recorder, substantially as shown and described.
